SUPPORT RACK FOR A GARDEN HOSE

Wallace D. Houchen, 3027 N. Sullivan Ave.,
Rosemead, Calif. 91770

Filed July 26, 1971, Ser. No. 165,880

Term of patent 14 years

Int. Cl. D6—99

U.S. Cl. D6—29

Fig. 1

FIG. 1 is a perspective view of a support rack for a garden hose showing my design; and

FIG. 2 is a view in side elevation with a portion of the rack shown broken away for convenience of illustration.

The broken lines shown in FIG. 2 are for illustrative purposes only.

I claim:

The ornamental design for a support rack for a garden hose, substantially as shown and described.
